Emery Parker

United States Patent Office.

EMERY PARKER, OF NEW BRITAIN, CONNECTICUT, ASSIGNOR TO RUSSELL AND ERWIN MANUFACTURING COMPANY, OF SAME PLACE.

Design No. 3,809, dated December 28, 1869.

DESIGN FOR A STRIKER-PLATE FOR A LOCK.

The Schedule referred to in these Letters Patent and making part of the same

To all whom it may concern:

Be it known that I, EMERY PARKER, of New Britain, in the county of Hartford, and State of Connecticut, have originated a new Design for a Striker-Plate for a lock or latch; and I do hereby declare that the following specification, taken in connection with the drawings, making a part of the same, is a full, clear, and exact description thereof.

A striker-plate for a lock, comprehends not only the projecting lip A, with a rounded edge, a, against which the bevel-face of the latch first strikes as the door shuts, but, also, the keepers B and C, for the latch and bolt respectively. It is also of sufficient length to admit of one or more screw-holes b, at each end, through which screws are inserted to fasten the plate to the jamb.

The edge of the plate is surrounded by a raised

band, c, which intersects with the plain surface of the plate immediately surrounding the keeper-mortise B of the latch. A similar raised band, d, surrounds the keeper-mortise for the bolt. The distinctive appearance of a sunken panel is thus given to the plate, in harmony with the design for a lock-front heretofore patented by me, and with locks of which character, this plate is proposed to be used.

What I claim as my invention, and desire to secure by Letters Patent, is—

The design for a striker-plate, substantially as herein described and shown in the drawings.

EMERY PARKER.
